SAFETY LOCKS FOR HARNESS

John J. O'Hara, 316 W. 14th St., New York 3, N.Y.

Filed May 14, 1958, Ser. No. 735,304

1 Claim. (Cl. 188—65.1)

My invention relates to safety devices for persons working or standing on scaffolds or other high places, and one of its objects is to provide a lock by means of which a harness or belt worn by a person can be secured to a life line or a rope hanging down from a fixed point.

Other objects are to connect the lock with the harness quickly, safely and disengageably, and for this purpose to provide the lock with an outer extension adapted to be engaged by a hook.

Further objects are to provide the lock with members adapted to grip the rope in a manner that strongly resists the unintentional release of the grip without damaging the fibers of the rope, for this purpose to clamp the rope between clamping members having concave gripping surfaces which extend like sectors of a vertical cylinder along a rope portion of considerable length, thereby to distribute the clamping pressure over a large surface of the rope whereby a large pressure can be exerted without damaging the texture of the rope, and to provide the clamping surfaces with rounded edges whereby these edges will not cut into the rope.

Still other objects are to press the clamping members toward the rope with large force, to provide handy means for releasing this pressure whereby the position of the lock on the rope can be adjusted, and to provide means which, upon this release, move the clamping members away from the rope whereby the adjustment of the lock can be made without friction, hence easily and without wear of the rope.

Still further objects are to attain these results with simple and inexpensive means, and to provide a lock structure that can be easily manufactured and comprises only a few parts which can be easily assembled.

Still other objects and advantages will appear from the following description of an exemplifying embodiment of my invention, from the appended claim and from the accompanying drawing in which:

Fig. 1 shows a cross-section of an illustrative embodiment of my invention, taken along the line 1—1 in Fig. 2.

Fig. 2 shows a cross-section taken along the line 2—2 in Fig. 1.

Fig. 3 shows a perspective view illustrating the use of the same embodiment in connection with a scaffold and represented on a much smaller scale than Figs. 1 and 2.

Referring to the drawing, numeral 3 indicates a lock shown in clamping engagement with a rope 4. This lock surrounds the rope and has a housing 5. The interior of this housing forms a channel going through the housing vertically from a bottom opening to a top opening. A bottom plate 6 preferably forms a separately made part of the housing and is affixed, for example screwed, to the housing 5 after the later described inner parts of the lock have been inserted whereby the assemblage of the lock is facilitated. The plate 6 has a central opening. The channel of the housing narrows upward along a conical inner housing surface 7 of which the axis is concentric with the rope 4.

An extension 8 of the housing forms a lateral projec-

2

tion and has an aperture or slot 9 whereby the housing is adapted for engagement by a hook connected to a harness.

A tube 11 reaches slidably through the opening of the plate 6 into the housing, surrounds the rope 4 slidably and preferably with a little clearance and extends upward as far as the surface 7. The part of this tube projecting downward from the housing may have a portion 12 of reduced diameter whereby this portion forms an easily gripped handle. The lower end 13 of the tube is preferably flared to facilitate introduction of the rope 4.

A plurality of clamping members is arranged about the rope 4 and distributed about the axis of this rope and of the conical surface 7. Each of these members has a part 14 shaped like a sector of a vertical cylinder and having a concave gripping side facing the rope. The edges of these surfaces are preferably rounded. Each of the clamping members further has a part 15 extending from the part 14 radially outward, passing slidably through a slot of the tube 11 and contacting the surface 7 with an outer side shaped obliquely at an angle fitting the conical slant of the surface 7.

Means are provided for urging the clamping members upward so that the resistance of the surface 7 presses them toward the rope. For example, a coiled spring 16 is positioned between the bottom 6 and the member parts 15 in compressed condition. Under the pressure of this spring, the clamping members move toward the housing axis until they grip firmly and compress slightly an elongated portion of the rope 4. In this condition which is shown in the drawing, the several clamping parts 14 may contact to form a closed ring about the rope and to prevent excessive compression of the rope. However, the aperture of the closed ring formed by the clamping members is of a diameter smaller than the diameter of the cable so that a positive, but not excessive, compression of the rope is obtained.

In order to release the rope, the tube 11 is pulled downward whereby the clamping members are also pulled down and are free to slide along the surface 7 and away from the rope. Thereby the pressure between clamping members and rope ceases, and the lock can be moved along the rope to adjust its position.

Preferably, means are provided which hold the clamping members in contact with the surface 7 also when the pressure is released in the manner described. Thereby the rope cannot only slide relatively to the lock, but is so far spaced from the clamping members that all friction and wear during such sliding is avoided. For this purpose, a flat spring 17 may be provided for each clamping member. This spring has ends bearing against the outside of the tube 11 and engages the member with its median portion which passes through a slot of the member part 15. In spread condition, the sectors 14 are a little spaced from each other.

Upon release of the tube 11, the spring 16 moves this tube and the clamping members up again whereby the interlocking condition is restored immediately.

The rope 4 constitutes a lifeline for the protection of a person positioned at considerable height. For example, this person may stand on a scaffold or a high board 18 suspended on tackles 19. If the board is long enough to carry two men, two lifelines 4 may be provided, each near one end of the board. Each lifeline is provided with a lock 3 which is affixed to the lifeline at a suitable height, for example, at the level of the belt of the man. When the level of the board is changed as it is necessary during the work at a high wall, the locks are shifted on the lifelines correspondingly in the manner described before.

The upper ends of the tackles and lifelines are secured in known manner independently from each other.

I desire it understood that my invention is not confined to the particular embodiment shown and described, the same being merely illustrative, and that my invention may be carried out in other ways within the scope of the appended claim without departing from the spirit of my invention as it is obvious that the particular embodiment shown and described is only one of the many that may be employed to attain the objects of my invention.

Having described the nature of my invention, what I claim and desire to protect by Letters Patent is:

A safety lock for a harness comprising a vertically hanging rope, a housing having a vertically through-going channel narrowing upward along a conical inner surface of said housing for receiving said rope, said housing being adapted to be engaged by a hook, a bottom affixed to said housing and having a central opening, a tube extending through said opening into said channel, a plurality of clamping members positioned in said housing and distributed about the axis of said conical inner surface and each having a part forming a section of a vertical cylinder and a part extending from said section outward through a slot of said tube into contact with said conical inner surface, a leaf spring mounted in each part with the opposite ends of the spring contacting said tube to urge said parts toward said conical inner surface, and a spring positioned between said bottom and said members and urging said members upward, the edges of the extended parts conforming in shape to the conical inner surface of said housing so that when said spring urges said members upwardly the complementary surfaces of

the housing and the extended parts move said clamping members into contact with said rope to retain said harness in selected adjusted positions on said rope.
